ATTORNEYS

UNITED STATES PATENT OFFICE.

CHARLES A. TATUM, OF NEW YORK, N. Y., ASSIGNOR TO WHITALL, TATUM & CO., OF SAME PLACE.

DESIGN FOR A BOTTLE.

SPECIFICATION forming part of Design No. 23,381, dated June 19, 1894.

Application filed May 23, 1894. Serial No. 512,234. Term of patent 14 years.

To all whom it may concern:

Be it known that I, CHARLES A. TATUM, a resident of the city, county, and State of New York, have invented and produced a new and original Design for Bottles, of which the following is a specification, reference being had to the accompanying drawings, in which—

Figure 1 shows an elevation of a bottle embodying my design; and Fig. 2 is a plan view thereof.

The essential feature of my design consists in a bottle ovaloid in horizontal section formed with inclined sides which taper from the base to near the top of the bottle, and thereupon

run vertically for a short distance to form a neck.

In the drawings, *a* represents the base of the bottle from which taper the sides *b* from which extend the neck *c* which is surmounted by a bead or lip *d*.

What I claim is—

The design for a bottle, substantially as shown and described.

CHARLES A. TATUM.
